US00D961628S

(12) **United States Design Patent** (10) **Patent No.:** **US D961,628 S**
(45) **Date of Patent:** **** Aug. 23, 2022**

(54) **TEXTILE MACHINE**

(71) Applicant: **SANTONI S.P.A.**, Brescia (IT)

(72) Inventors: **Ettore Lonati**, Botticino (IT); **Fausto Lonati**, Brescia (IT); **Andrea Lonati**, Brescia (IT)

(73) Assignee: **SANTONI S.P.A.**, Brescia (IT)

(**) Term: **15 Years**

(21) Appl. No.: **29/717,578**

(22) Filed: **Dec. 18, 2019**

(30) **Foreign Application Priority Data**

Jun. 18, 2019 (EM) 006583290-0005

(51) **LOC (13) Cl.** **15-06**

(52) **U.S. Cl.**

USPC **D15/66; D15/72**

(58) **Field of Classification Search**

USPC .... D15/66-78; 66/8, 151, 108 R, 17, 178 R, 66/57, 104, 125 R, 20, 64, 13, 132 R, 14, 66/140 S, 145 R, 148, 149 R, 153, 222;

D3/29

CPC . D04B 13/00; D04B 13/02; D04B 9/00-9/58; D04B 15/06; D04B 15/14; D04B 15/88; D04B 15/94; D05B 1/00-25/00; D03D 49/12; D03D 49/16

See application file for complete search history.

(57) **CLAIM**

The ornamental design for a textile machine, as shown and described.

DESCRIPTION

FIG. 1 is a perspective view of a textile machine;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof; and,

FIG. 7 is a right-side elevational view thereof.

The broken lines in the drawings depict portions of the textile machine that form no part of the claimed design.

1 Claim, 6 Drawing Sheets
